UNITED STATES PATENT OFFICE.

JONATHAN PETERSON, OF BROOKLYN, NEW YORK, ASSIGNOR TO COMBINATION MACHINE COMPANY, OF NEW YORK, N. Y., A CORPORATION OF DELAWARE.

METHOD OF PACKING AND PRESERVING PLUG-TOBACCO.

1,398,568.

Specification of Letters Patent. Patented Nov. 29, 1921.

Application filed April 11, 1921. Serial No. 460,601.

To all whom it may concern:

Be it known that I, JONATHAN PETERSON, a citizen of the United States, and resident of Brooklyn, in the county of Kings and 5 State of New York, have invented certain new and useful Improvements in Methods of Packing and Preserving Plug-Tobacco, of which the following is a specification.

This invention relates to a method of packing and preserving tobacco plugs or cakes and to the plug package resulting therefrom, and relates more particularly to a method and article of the nature referred to in which a package containing a plurality of 15 tobacco plugs or cakes is put up in relatively small units and in which the plugs are preserved for an indefinite time in their original condition as regards moisture content, flavor and other characteristics; and has special 20 reference to the provision of such a package especially adapted for the retail trade in which each unit plug is kept in preserved condition, such unit being detachable from the package for purposes of sale, the detaching 25 of a unit leaving the remaining units in intact and fully preserved condition.

A common method hitherto employed in packaging tobacco plugs or cakes has involved the packaging of a large quantity of 30 plugs in "caddies" or large cases made of expensive wood stock and especially constructed to preserve the plugs against deterioration from the elements. In order to reduce the cost of packaging per unit plug it 35 has been the practice to package a large number of plugs in a single case, some "caddies" containing as many as 48 pounds of tobacco plugs. This procedure has involved many disadvantages, prime among which 40 has been the inability to successfully cater to the demands of the small retail dealers who find it inconvenient and moreover uneconomical to handle large stocks of an article for which there may be a relatively small 45 "call", the plugs when kept in stock for some period of time after the case or package is first opened being subject to relatively rapid deterioration, such plugs losing their moisture, flavor and other desirable properties 50 and becoming dry and brittle when open to air and atmospheric moisture. A prime desideratum of my present invention therefore involves the production of a plug package in which a relatively small number of plugs are 55 put up in packages of small capacity such as,

for example, of one or two pounds, the cost of the packaging operations being a negligible factor as regards each unit plug, the plugs being, furthermore, packaged so that each plug is kept in a preserved condition up 60 to and including the time of sale to the consumer, the sale of one plug not affecting the packaging or preservation of any of the other plugs in the package.

Tobacco plugs are usually made and sold 65 in compressed or compacted blocks, each unit or block comprising a tobacco leaf filler covered by a leaf wrapper. I have found it desirable to preserve each block or unit by packing such block or unit in a wrapper 70 impervious to air or moisture, the unit block being so inclosed by the wrapper that all air pockets are ironed out and eliminated, the wrapper being then sealed against entry of air or moisture. A package made up of a 75 plug provided with an impervious wrapper such as a wrapper having a coating of paraffin or wax; the wrapper and plug being compressed or compacted into a unit, the wrapper adhering closely to the faces of the 80 packet, has been found highly efficient for this purpose. In producing such a package, however, it is desirable not to injure the tobacco product packaged, as the preservation 85 of the plug, especially the preservation of the wrapper leaf in undamaged condition is a factor in keeping the product in a preserved state. Furthermore, it is desired to so inclose the plug that the wrapper will adhere to the face of the plug without "sticking" 90 thereto and without affecting the cohesion between the tobacco leaf wrapper and the filler inclosed thereby, the plug being removable from the wrapper without the necessity of having to strip the wrapper from 95 the unit plug; such a construction permitting the obtaining of a plug in undamaged or unmutilated form for consuming use. My present invention therefore further comprehends the provision of a plug package in 100 which the wrapper adheringly fits the packaged plug without sticking thereto, the package not only being preserved against action by the elements, but being kept in undamaged condition and being obtainable in a 105 fresh and unmutilated state when required for consuming use.

The principal objects of my invention therefore include, besides the provision of a plug package containing a plurality of 110

separable plugs or cakes, each plug being packed for purposes of preserving the same up to the time of its consumption; the provision of such a package having a small 5 number of plug units in a package especially adapted for the retail trade; the provision of such a package in which each plug unit is preserved independently of the others; a plurality of such unit plugs making up a 10 sealed package, a plug being adapted to be detached and sold without breaking the seal of the remaining plugs in the unit package; the further provision of such a package in which each plug is closely incased 15 by a wrapper, the wrapper closely adhering to the faces of the plug for eliminating air pockets and sealing the plug against entry of air or moisture, the tight wrapper not affecting the integrity of the packaged plug 20 commodity and the provision of such a package in which the units may be assembled and packed by simple manufacturing steps, the cost of packaging being a negligible component of the cost of the packaged 25 commodity.

To the accomplishment of the foregoing and such other objects as may hereinafter appear, my invention consists in the elements and their relation one to the other, 30 as hereinafter particularly described and sought to be defined in the claims, reference being had to the accompanying drawings which show a preferred embodiment of my invention and in which:

35 Figure 1 is a perspective view showing the manner of assembling the plugs to form an integral plug package,

Fig. 2 is a cross sectional view of the same;

40 Fig. 3 is a perspective view showing a completed plug package as it appears after the compacting operation, with parts broken away to show the interior package laminations,

45 Fig. 4 is a perspective view of the package inclosed in an outer enveloping wrapper,

Fig. 5 is a perspective view showing the manner of detaching a plug from the assembled formation, and

50 Fig. 6 is a view of the completed package with an outer carton covering the enveloping wrapper.

In the drawings my invention is shown applied to the packaging of tobacco plugs 55 compressed or compacted in rectangular block formation, but it will be understood that I do not intend to limit my invention to the packaging of such a product, as my invention is of broader utility and may be 60 used for the preservation and packaging of other products or commodities where similar problems are involved. My invention contemplates primarily the assembling of a plurality of unit plugs to make up an 65 integral package of relatively small capac-

ity, such as a one or two pound package, for example, each plug unit retaining its identity in the integral package, each plug being retained in a fully preserved state up to the time of its use, each such unit plug 70 being detachable or removable from the package when desired for sale or use, removal of such plug having no effect on the packaging or preservation of the remaining plugs in the package. To this end I arrange 75 a plurality or series of tobacco plugs or cakes in alternation with a plurality of wrappers therefor, a wrapper being provided for each plug, the wrappers having marginal portions overlying the side walls 80 of the plugs, the whole when assembled and packed forming a laminated package. This method of assembly is shown in Figs. 1 and 2 of the drawings, the resulting integral package being depicted in Fig. 3. A plurality of series of plug layers such as 10 each comprising a compressed plug having the usual tobacco leaf 11 covered by the tobacco leaf wrapper 12 are assembled in alternation with a plurality or series of layers of wrappers 13, each wrapper 13 being provided with marginal portions or laps 14 of a width sufficient to overlie the side walls 90 of the plugs and to overlie the marginal portions of one or more adjacent wrappers for 95 a purpose that will appear presently.

For the purpose of facilitating assembly of the plug units, which may be carried out by hand, I prefer to perform or prefold each wrapper by suitable apparatus, each wrapper being preformed to provide the side and end laps 14 and the corner folds 15; such prefolding providing substantially dish-shaped wrappers or containers. In making the assembly a plug 10 is inserted in a 100 dish-shaped wrapper, the wrapper being so prefolded that substantially equal width end and side laps 14 are provided, this affording a properly centered plug in a wrapper, the bottom of each dished wrapper 110 having a configuration and area equal to that of a bottom face of a plug so that when the laps are folded and pressed against side walls of the plugs the wrappers will fittingly envelop the plug faces. The alternate wrappers and plugs are assembled in 115 nested relation, as shown in Figs. 1 and 2 of the drawings, until a one or two pound package is formed as is desired, the assembly being then ready for subsequent compacting and packing operations.

It is desired to provide a package wherein each of the plugs may be protected against the elements for an indefinite time to preserve the desirable properties of the product, 125 such as its moisture content, flavor, pliability and other characteristics, and to this end I provide wrappers having an impervious coating such as of wax or paraffin, each of the plugs being hermetically sealed 130

by such impervious wrappers. Accordingly, I provide each of the wrappers 13 with an impervious coating of wax or paraffin, such as shown at 16.

- 5 After the assembly shown in Figs. 1 and 2 is formed, the assembled formation is compressed or compacted into an integral package in such manner that all interior air pockets are eliminated, the bottom face of 10 each plug being compressed in intimate and adhering contact with the interior face of each wrapper bottom, the wrapper laps being compressed against the side walls of the plugs in like intimate contact. It is desired, 15 however, that each wrapper so inclose the plug that although the wrapper faces adheringly envelop the plug faces, that such wrapper faces do not "stick" to the plug to prevent free removal of the plug from 20 its wrapper when the plug is required for use, it being further required that the use of an impervious wrapper otherwise have no deleterious effect on the packaged plug; and that such plug be obtainable when desired 25 for consumption in whole and undamaged state. To this end the wrapper is provided with a single coating 16 of wax or paraffin, such coating being provided on the outer faces or walls only of each dish-shaped wrapper, as clearly shown in the 30 drawings.

In order to prevent the wax or paraffin coated outer faces of a wrapper bottom from sticking to the top face of an adjacent plug unit, I preferably interpose a separating blank or sheet between a plug of one unit and the wrapper of the next adjacent unit, such a sheet being shown as 17 in the figures. My assembly therefore preferably consists 35 in first selecting a dished wrapper 13, inserting therein a cake or plug 10 and placing on the plug a separating blank or sheet 17 and repeating this cycle or process until a one or two pound assembly results, the 40 assembled formation being then ready for the compacting or compressing operation.

As hereinbefore referred to the plug assembly is compacted or compressed by suitable apparatus and preferably under application of heat, to the end that substantially 45 all the interior air pockets be ironed out or eliminated, the bottom and top plug faces of each plug being adheringly covered by a wrapper face and a separating blank respectively, the top face of the uppermost plug being preferably protectively enclosed by the blank 18, shown in Fig. 3 of the drawings, the said blank having an impervious coating on the outside face thereof. The 50 wrapper laps 14 and folds 15 are compressed into overlapping and overlying relation, as clearly shown in Fig. 3 of the drawings, these laps being preferably of a width two or more times the thickness of a plug or 55 cake, so that a multiply covering for the

side walls of each cake is provided. Such a multiply covering affords increased protection to the plug, especially at the cut faces thereof where evaporation of the juices more rapidly takes place. By the compressing 70 operation, which is preferably carried on under application of heat, the overlying wrapper laps adhere to each other, the wrapper joints being effectively wax or paraffin welded, as shown at 19 in Fig. 3 of the 75 drawings. The package as a whole forms an integral package, each plug being hermetically sealed against atmospheric influences, most of the plug units not only being protected by the impervious wrappers, but 80 by the protective walls offered by the adjacent plug or plugs.

After the assembled and compressed formation shown in Fig. 3 is obtained, I contemplate enveloping the assembly in wrapping and carton means to make up a finished packet which may be handled as such by the trade. To this end I first envelop the compressed assembly in an enveloping wrapper 20, as shown in Figs. 4 and 6 of the drawings, adhesive bands 21 and 22 being preferably provided to close the overlapping wrapper folds, the band or strip 22 being preferably arranged longitudinally of the packet to aid in maintaining the packet into an 95 integral unit.

As hereinbefore referred to, the elimination of air spaces and pockets in the plug package has been found to be one of the conditions precedent necessary to the obtaining 100 of a package in which the plugs are kept in a fully preserved state. It oft-times occurs that the side walls of the wrapper packet shown in Fig. 4 of the drawings, instead of presenting flat faces, present irregular faces. 105 With such irregular faces or walls the inclosing of a packet in an outer carton, which is usually made of paper board, results in the formation of air spaces and pockets between the carton walls and the packet walls. 110 I have found it desirable to provide a construction which will minimize or eliminate such air spaces and pockets. To accomplish this end I have found it desirable to use a compressible board for the carton base and 115 to compress such board against the walls of the packet, the carton board accommodating itself to the irregularities of the packet faces. Accordingly, I provide a carton made preferably of corrugated board, as shown at 120 23 in Fig. 6, the said board comprising outer and inner layers 24 and 25 respectively, and an intermediate layer 26 of sinuous configuration providing air flutes, the whole forming a yieldable carton which may be compressed against the packet side walls, the inner carton layer 25 following the irregularities of the packet walls, thus eliminating the air pockets between the carton and such walls. The outer carton 23 is also prefer- 125 130

ably provided with an adhesive band or strip 27 closing the carton folds, a completed intact package being in this manner provided.

5 The manner of assembly and packing my plug package will be apparent from the above detailed description thereof. The finished integral plug package is sold to the retail trade in the form shown in Fig. 6 in 10 small units of, for example, one or two pounds. When a plug is desired for sale or consumption the outer carton 23 and the enveloping wrapper 20 are removed, presenting a package as shown in Fig. 3 of the 15 drawings. The bottom plug is then removed in a manner illustrated in Fig. 6 of the drawings, the skirt provided by the wrapper laps of the top wrapper being pried loose from the other wrapper laps, the bottom wrapper 20 and its plug being separated and removed for such sale and use. Only the seal of the 25 bottom wrapper need be broken, the bottom plug being thus removable without affecting the integrity of the remainder of the integral package, the remaining plugs being retained in packaged and sealed condition, each of such remaining plugs being preserved in packaged formation until such 30 plug is in turn required for use.

30 It will be apparent from the foregoing that I have provided a plug package especially adapted for the retail trade, eliminating the use of "caddies" or large containers 35 hitherto employed with the disadvantages consequent thereto, my integral plug package being provided in a simple manner and at a low manufacturing cost, each package being so packed that each plug is preserved against air or moisture, every plug being so 40 preserved up to the time of sale to the consumer. Although a plurality of plugs are put into a single package to minimize the cost of enveloping and packing and for other reasons, each plug may be detached 45 from the packaged unit without affecting the integrity of the other plug units for the preservation thereof. Each plug is so packed as to eliminate air pockets, a wrapper closely adhering to the plug 50 protectively inclosing and sealing the same, the plural plug formation increasing the protection, especially for the intermediate plugs, all securing a compacted plug formation 55 eliminating air pockets and sealing the same against moisture or air. Although the wrapper closely adheres to the faces of the 60 plug, the adhesion is such that no sticking between the plug faces and the wrapper faces results. In this way each plug is kept 65 in undamaged or unmutilated state and may be removed from the wrapper in such condition for use. For the purpose of facilitating packing, the wrappers are preformed and are made dish-shaped, this also providing a wrapper the laps of which are sure

to overlie all the side walls of the plugs, the plugs being centered in the wrappers and fittingly enveloped thereby. The wrapper laps are made sufficiently long so that adjacent laps provide a multiply covering for the 70 side walls of the plugs, preventing evaporation of any of the juices having free access at the side walls and preventing absorption of moisture at these parts. All the wrapper joints are welded, this being secured by the 75 compacting and compressing operations preferably under application of heat, all the plugs making up the compacted integral package. Such package is, furthermore, wrapped in an outer wrapper and inclosed 80 in a compressible or corrugated board carton, such carton accommodating itself to the irregular faces of the plug package for the purpose of eliminating air spaces between the carton faces and the faces of the plug 85 package.

It will be understood that while I have shown my plug package as comprising impervious wrappers such as wax or paraffin coated wrappers, I do not intend to limit my 90 invention to the use of such wrappers, it being apparent that I may use with equal facility other types of wrappers such as, for example, foil wrappers and more particularly tin or lead foil, especially such foil 95 wrappers which can be fused to provide imperviously sealed joints.

While I have shown my device in the preferred form, it will be obvious that other changes and modifications may be made in 100 the structure disclosed without departing from the spirit of the invention, defined in the following claims.

I claim:

1. A package of plug tobacco comprising 105 a plurality of layers of tobacco plugs or cakes alternating with a plurality of layers of wrappers therefor; the wrappers being provided with marginal portions forming laps overlying the sides of the plugs, the 110 whole being compressed into a substantially solid block forming a laminated package.

2. A package of plug tobacco comprising 115 a plurality of layers of tobacco plugs or cakes alternating with a plurality of layers of wrappers therefor; the wrappers being provided with marginal portions forming laps overlying the sides of the plugs, the marginal laps of a wrapper being arranged to overlap the marginal laps of the next 120 adjacent wrapper, the construction providing a multiply lap formation overlying the side walls of the plugs, the whole being compressed into a substantially solid block forming a laminated package.

3. A package of plug tobacco comprising 125 a plurality of layers of tobacco plugs or cakes alternating with a plurality of layers of impervious wrapper sheets therefor; the wrapper sheets being folded to provide 130

marginal portions forming laps overlying the sides of the plugs, the whole being compressed and forming a substantially solid laminated package.

5. 4. A package of plug tobacco comprising a plurality of layers of tobacco plugs or cakes alternating with a plurality of layers of impervious wrappers therefor; the wrappers being provided with marginal portions 10 forming laps overlying the sides of the plugs, the marginal laps of a wrapper being arranged to overlap the marginal laps of the next adjacent wrapper, the joints between the laps being hermetically sealed; the construction providing a multiply lap formation overlying the sides of the plugs, the whole forming a laminated package.
5. A package of plug tobacco comprising a plurality of layers of tobacco plugs or 20 cakes alternating with a plurality of layers of paraffin or wax coated wrappers therefor; the wrappers being provided with marginal portions forming laps overlying the sides of the plugs, the joints between laps of adjacent wrappers being hermetically wax 25 welded, the whole being compressed and forming a substantially solid laminated package.
6. A package of plug tobacco comprising 30 a plurality of nested dish shaped wrapper sheets alternating with a plurality of layers of tobacco plugs or cakes, each wrapper sheet adheringly inclosing a tobacco plug; a plug and its wrapper sheet forming a detachable unit, the side walls or laps of the 35 wrapper sheet being arranged in relative overlapping relationship, the whole forming a compacted laminated package.
7. A package of plug tobacco comprising 40 a plurality of nested dish shaped wrappers or containers alternating with a plurality of layers of tobacco plugs or cakes, each wrapper being provided with a coating of paraffin or wax on the outer walls thereof, each 45 wrapper adheringly inclosing a tobacco plug; a plug and its wrapper forming a detachable unit; the side walls or laps of the 50 wrapper being arranged in relative overlapping relationship, the joints between the overlapping wrapper walls being wax welded, the whole forming a laminated package.
8. A package of plug tobacco comprising 55 a plurality of nested dish shaped wrappers or containers alternating with a plurality of layers of tobacco plugs or cakes, each wrapper adheringly inclosing a tobacco plug; a plug and its wrapper forming a detachable unit, a separating sheet between a 60 plug of one unit and a wrapper of the next adjacent unit, the side walls or laps of the 65 wrapper being arranged in relative overlapping relationship, the whole forming a laminated package.
9. A package of plug tobacco comprising 70 a plurality of nested dish shaped wrappers or containers alternating with a plurality of layers of tobacco plugs or cakes each wrapper being provided with a coating of paraffin or wax on the outer walls thereof, each wrapper adheringly inclosing a tobacco 75 plug; a plug and its wrapper forming a detachable unit, a separating sheet between a plug of one unit and a wrapper of the next adjacent unit; said walls or laps of the wrapper being arranged in relative overlapping relationship, the joints between the overlapping wrapper walls being wax welded, the whole forming a laminated package.
10. A package of plug tobacco comprising 80 a plurality of layers of tobacco plugs or cakes alternating with a plurality of layers of wrappers therefor; the wrappers being provided with marginal portions forming laps overlying the sides of the plugs, the whole being compressed into the 85 form of a substantially solid laminated block-like package, an outer wrapper enveloping the package and a carton inclosing the package and the enveloping wrapper, the carton comprising a compressible board compactly inclosing the package.
11. A package of plug tobacco comprising 90 a plurality of tobacco plug units each hermetically sealed, the plurality of units forming a stack or "butt" package, and outer wrapper enveloping the package, and a carton inclosing the package and wrapper, the carton including corrugated board compactly inclosing the package, the inner faces of the carton accommodating the irregularities of the package for the elimination of air spaces or pockets.
12. A package of plug tobacco comprising 95 a plurality of tobacco plug units each hermetically sealed, the plurality of units forming a stack or "butt" package, outer wrapping means therefor including a carton inclosing the package, the carton including corrugated board compactly inclosing the package, the inner faces of the carton 100 accommodating the irregularities of the package for the elimination of air spaces or pockets.
13. The method of packing and preserving 105 plug tobacco, which consists in assembling a plurality of tobacco plugs or cakes in alternation with a plurality of wrapper sheets, the wrapper sheets being provided with marginal portions, infolding the marginal portions to overlie the side walls of 110 the tobacco plugs or cakes, the marginal portions of adjacent wrappers being arranged in overlapping relationship whereby a laminated plug package is provided.
14. The method of packing and preserving 115 plug tobacco, which consists in assembling a plurality of tobacco plugs or cakes in alternation with a plurality of wrapper sheets, the wrapper sheets being provided with marginal portions, in folding the mar- 120

ginal portions to overlie the side walls of the tobacco plugs or cakes, the marginal portions of adjacent wrappers being arranged in overlapping relationship, and in 5 wax welding the joints between the overlapping marginal portions, whereby a laminated plug package is provided.

15. The method of packing and preserving plug tobacco which consists in assembling a 10 plurality of tobacco plugs or cakes in alternation with a plurality of wrapper sheets, each sheet being provided with an impervious coating such as wax or paraffin on one face thereof, the wrapper sheets being 15 provided with marginal portions, in folding the marginal portions to overlie the side walls of the tobacco plugs or cakes with the coated wrapper faces forming the outer faces of the package, the marginal portions of adjacent 20 wrappers being arranged in overlapping relation and in then compacting or compressing the package and welding the joints between wrappers whereby a laminated impervious plug package is provided.
- 25 16. The method of packing and preserving plug tobacco, which consists in assembling a plurality of pre-formed dish shaped wrapper sheets in nested relation and alternating with a plurality of layers of tobacco plugs or 30 cakes, each wrapper sheet containing a plug; a plug and its wrapper forming a unit, in

then folding and compacting the marginal laps of the wrapper in compacted and overlying relation on the side walls of the plugs, the marginal laps of adjacent wrappers being arranged in overlapping relationship, the joints between the laps being welded, whereby a sealed laminated plug package is provided.

- 35 17. The method of packing and preserving 40 plug tobacco, which consists in assembling a plurality of pre-formed dish shaped wrappers in nested relation and alternating with a plurality of layers of tobacco plugs or cakes, each wrapper having an impervious coating on the outer walls thereof, each 45 wrapper containing a plug, a plug and its wrapper forming a unit, in interposing a separating sheet between a plug of each unit and a wrapper of the next adjacent unit, and in then folding and compacting the marginal laps of the wrapper in compacted and overlying relation on the side walls of the plugs, the marginal laps of adjacent wrappers being arranged in overlapping relationship, the joints between the laps being 50 welded, whereby a sealed laminated plug package is provided.

55 Signed at New York in the county of New York and State of New York this 8th day of April A. D. 1921.

JONATHAN PETERSON.
